UNITED STATES PATENT OFFICE

HARRY R. PRIEST, OF LOUDONVILLE, OHIO

TOOTH CLEANER AND POLISHER

Application filed July 12, 1930. Serial No. 467,607.

This invention relates to tooth cleaners and polishers and has for an object to provide a device employing a cleaning and polishing element preferably formed of a short compact tuft of stiff bristles, such as badger bristles, the shank of the device being so constructed that pressure up to and beyond eighteen pounds may be applied so that film, stain, or tartar may be readily removed.

A still further object of the invention is to provide a tooth cleaner and polisher having a magazine for feeding tooth paste to the cleaning and polishing element sufficient to accomplish the desired result without waste of tooth paste, thus promoting economy in upkeep.

A still further object of the invention is to provide a case for the tooth cleaner and polisher which will ventilate the cleaning and polishing element adequately and will employ a mirror which may be used in connection with a second mirror carried in the magazine cap of the tooth cleaner and polisher to permit thorough inspection of the teeth.

A still further object of the invention is to provide a tooth cleaner and polisher having the cleaning and polishing tuft removably assembled in a short annular hollow head which is abruptly offset from the end of the shank, the head being curved on the exterior surfaces thereof so as to permit of the cleaning and polishing element being inserted in the mouth to clean the fronts or backs of the teeth in a vertical direction from the gums to the biting edges thereof as well as permitting the device to be comfortably and quickly manipulated to assume various angular positions so that portions of the teeth never reached by ordinary tooth brushes may be quickly reached for thorough cleaning and polishing.

With the above and other objects in view the invention consists in certain novel details of construction and combinations of parts hereinafter fully described and claimed, it being understood that various modifications may be resorted to within the scope of the appended claims without de-

parting from the spirit or sacrificing any of the advantages of the invention.

In the accompanying drawings forming part of this specification,

Fig. 1 is a perspective view showing the case with the mirror end of the cleaning and polishing tool exposed,

Fig. 2 is a perspective view of the cleaning and polishing tool,

Fig. 3 is a longitudinal section taken on the line 3—3 of Fig. 1, and

Fig. 4 is an end elevation showing the mirror end of the case.

Referring now to the drawings in which like characters of reference designate similar parts in the various views, 10 designates a substantially cylindrical shank which is provided with an axial duct 11 and terminates at one end in a head 12. The head is abruptly directed laterally to extend at substantially a right angle to the shank and is relatively short, as best shown in Figs. 2 and 3. The shank is reduced in outer diameter, as shown at 13, adjacent to the head so as to provide space for the lips when the tool is in operation. The head is annular and internally threaded, as shown at 14.

A cleaning and polishing element is screwed into the head and comprises a short annular socket 15 having a reduced threaded stem 16 adapted to screw into the threaded head 12. The socket is provided with an axial duct 17.

Preferably, a single tuft 18 of comparatively stiff bristles, such as badger bristles, is rigidly secured in the socket 15. A hard rubber base 19 is preferably employed to surround and bind together the bristles of the tuft and the base is preferably forced into the socket by a driving fit or otherwise so as to prevent any possibility of the parts becoming separated from each other. Thus the socket carrying the tuft of bristles is removably secured in the head so that replacement of this part alone is necessary when worn out instead of discarding the whole tool, as is ordinarily done.

It will be noted that the exterior surface of the head is rounded or curved throughout so as to promote manipulation of the

tool in the mouth. It will be also noted that by virtue of the short compact bristle element being carried by the head at substantially a right angle to the shank, and the shank being reduced, as shown at 13, the tool 5 may be easily inserted in the mouth and turned at an angle sufficient to reach the backs of the teeth as well as the crevices therebetween, and also the biting edges of 10 the rearmost teeth in the mouth, both upper and lower teeth.

It will be also pointed out that great pressure may be applied to the tool to effect the thorough removal of stains, film and tartar 15 whereby the true luster and polish of the teeth may be exposed. Ordinary tooth brushes are found in actual practice to be incapable of resisting the application of sufficient pressure to remove stains and tartar 20 since the bristles spread apart and thus are ineffective. Even the handles break. Actual scale tests show that up to 2½ pounds pressure the bristles of an ordinary tooth brush, due to their hinge action when 25 pressure is applied, spread apart and become entirely ineffective. Furthermore, the handles under actual scale tests are found to break or bend at from 8 to 12 pounds pressure.

30 It is well known to those skilled in the art of dentistry that from 10 to 15 pounds pressure is necessary to remove tartar. By virtue of the novel construction of the shank, head, socket, and single bristle tuft 25 above described, the tool has been found to be unaffected by pressure applied to the same of approximately 20 pounds. This pressure resisting feature is inherent in the tool constructed as above described, that is, the structure described produces a tool 40 which will effectively begin its work in removing stains, mucus films, and tartar where the old and well known types of tooth brushes fail to function.

45 By referring now to Figs. 2 and 3, it will be seen that a cylindrical magazine 20 is provided with interior screw threads 21 throughout its length to engage exterior screw threads 22 formed on the free end of 50 the shank 10. The magazine is closed by a flanged exteriorly threaded cap 23, removal of which permits of the magazine being filled with tooth paste of any preferred type. The flange 24 of the cap is provided 55 in the outer face thereof with a mirror 25, the mirror being preferably counter-sunk in the flat face of the flange. The flange, it will be noted by referring to Fig. 3, extends considerably beyond the outer face of the 60 magazine for a purpose which will presently appear. To supply the tooth paste to the bristles 18, it is simply necessary to advance the magazine a quarter turn whereupon sufficient paste will be ejected through 65 the ducts 11 and 17 to efficiently clean and

polish the teeth. A reverse turn of the magazine prevents further escape of the tooth paste. Economy is greatly promoted, since by virtue of there being but a single tuft of bristles, a minimum quantity of 70 paste may be used in each operation in contrast to the long ribbon of paste usually spread upon the ordinary tooth brush, most of which is wasted.

A carrying case 26 of substantially cylindrical form is provided for housing the tool, the case preferably being closed at one end and receiving a mirror 27 which preferably is counter-sunk in the end wall of the case. The case is provided with a series of ventilating openings 28 adjacent 75 to the closed end thereof.

The case is open at one end and is beveled, as shown at 29, to receive the flange 24 of the magazine cap 23, whereby the tool is 80 frictionally held in the case. To remove the cleaning and polishing tool from the case, it is simply necessary to grasp the case in one hand and tap it against the palm of the other hand, whereupon the tool will be 85 dislodged longitudinally from the case.

Having thus described the invention, I claim:

1. A tooth cleaning and polishing tool comprising a shank having a duct therethrough, a magazine carried by the shank for supplying tooth paste through said duct, said shank terminating in a substantially annular hollow head extending laterally from the shank, said head being relatively short in length and being interiorly threaded, a socket screwed into said head and having an axial duct communicating with the duct of the shank, and a single tuft of relatively short stiff bristles rigidly secured in 95 said socket and extending at substantially 100 a right angle to the axis of said shank.

2. A tooth cleaning and polishing tool comprising a shank threaded exteriorly at one end and having the opposite end uniformly reduced to form a curved surface for receiving the lips when the tool is applied to the teeth, said shank terminating contiguous to said curved portion in a hollow annular short head interiorly threaded, 110 said shank and head having axial ducts therethrough, a socket threaded into said head, a compact unitary tuft of stiff bristles integrally secured in said socket, said tuft and said socket extending laterally at substantially a right angle to said shank, said head being round exteriorly to facilitate manipulation of the tuft against the teeth from the gums to the biting edges thereof without injury to the soft tissues of the mouth, a 115 magazine for tooth paste screwed onto the threaded end of the shank, and a filling cap for the magazine.

3. A tooth cleaning and polishing tool comprising a shank having an axial duct 120

and terminating in a laterally disposed short annular hollow head, a socket removably secured in said head and having a tuft of bristles integral therewith, a tooth paste magazine carried by said shank and movable longitudinally thereof to compress tooth paste and force the same through said duct to said tuft, a cap closing the filling end of said magazine, a mirror carried by said cap, and a case enclosing said shank and magazine and having an open end frictionally engaging said cap whereby said cap forms a closure for the open end of said case.

4. A tooth cleaning and polishing tool comprising a shank of substantially cylindrical contour and having a reduced end to provide a curved surface for receiving the lips during manipulation of the tool, said shank terminating contiguous to said curved surface in a laterally offset relatively short hollow head, a socket removably secured in said head, a tuft of bristles carried by said socket, said shank having an axial duct for supplying tooth paste to said bristles through said head and said socket, a magazine having a screw thread connection with said shank remote from said head and adapted to be advanced longitudinally of said shank to compress tooth paste and eject the same through said duct into said tuft, a flanged cap threaded into the filling end of said magazine, the flange of said cap projecting exteriorly beyond the exterior of the magazine, and a case enclosing said shank and said magazine and having a beveled open end frictionally engaging the flange of said cap, said cap forming a closure for said open end of the case, there being ventilating openings formed in the case remote from said open end.

In testimony whereof I affix my signature.
HARRY R. PRIEST. [L. S.]
